[57] CLAIM

The ornamental design for a serving table, substantially as shown and described.

DESCRIPTION

FIG. 1 is a front perspective view of a serving table showing my new design;

FIG. 2 is a bottom plan view thereof;

FIG. 3 is a side elevational view thereof;

FIG. 4 is an elevational view thereof taken from the side opposite that shown in FIG. 3; and

FIG. 5 is a rear elevational view thereof.
